Application July 16, 1956, Serial No. 597,974

5 Claims. (Cl. 2—145)

This invention relates to necktie holders of the type having means adapted to engage a button of the shirt with which it is worn to retain the free ends of a knotted tie smoothly in place close to the shirt front.

An important object of the invention is to provide a necktie holder of the kind disclosed in my Patent No. 2,013,061 dated September 3, 1935, incorporating improved means for attaching the tie to the shirt button, such improved attaching means comprising a flat disk of stiffly flexible material connected by a stretchable cord to the rear face of the outer one of the two free ends of the necktie and capable of being snapped over a shirt button.

Another object of the invention is to provide an attaching means of the above character which is simple and inexpensive in construction and which avoids the possibility of breaking the cord or pulling the button off the shirt in the event an outward tug is exerted upon the necktie, such as is likely to occur through failure to disconnect the disk from the shirt button when the necktie is being removed from the shirt.

Still another object of the invention is to provide an attaching means of the above character which may be permanently connected to the necktie and which will not interfere with the laundering or dry cleaning of the necktie.

Other objects and advantages will be apparent from the following detailed description of a preferred embodiment of the invention, reference being made to the accompanying drawing in which:

Figure 1 is a front of a necktie as it is normally worn with a section through the necktie being broken away to show the front of a shirt and the means for attaching the necktie to a shirt button;

Figure 2 is a side view of the necktie, shirt and attaching means of Figure 1;

Figure 3 is a detail plan view of the necktie attaching means; and

Figure 4 is a cross-sectional view through the disk taken on the line 4—4 of Figure 3.

In the drawing the two overlapping lower ends 1 and 1a of a conventional four-in-hand tie are shown overlying the front of a shirt 2. A flexible cord 3 is secured to the rear face of the outer end 1 of the necktie, the two free ends of the cord being stitched to the necktie a spaced distance apart and the midportion of the cord passing through a pair of relatively widely spaced apart perforations 4 and 4a in the edge of a thin disk 5 in a manner such that the disk is freely slideable upon the cord. By providing a pair of apertures 4 and 4a instead of a single aperture, the cord is prevented from twisting together, which would interfere with the stretch of the cord. The cord is preferably made of nylon or other textile material having a limited amount of elasticity or "stretch" but which possesses sufficient strength to resist being easily broken by tugs and strains.

The disk 5 is preferably of circular shape and composed of a stiffly-flexible material, such as Celluloid or other plastic or possibly sheet metal. The disk is punched out between its marginal edges to produce a generally

rectangular slot 6 extending horizontally across the disk parallel to a line connecting the perforations 4 and 4a and terminating in two vertical slots 6a which together define an upwardly projecting tongue 7. The tongue 6 normally lies in the plane of the disk and by reason of its resilient nature it is capable of being flexed outwardly of the disk, as indicated in dotted lines in Figure 4, to admit the shirt button into the slot 6.

In the use of the device, the necktie is drawn through the collar of the shirt and knotted in the usual manner with the two free ends of the necktie overlying the shirt front. The underlying end of the necktie is passed through the loop of the cord 3 and the cord is stretched so that the disk overlies a button B on the shirt front. By pressing the disk 5 against the button the tongue 7 yields to pass the button through the slot after which the tongue springs back to yieldingly engage the stitching by which the button is sewed to the shirt. The cord is thus held in slightly stretched condition and retains the two free ends of the necktie snugly and smoothly against the shirt. To detach the tie-holder from the shirt it is only necessary to exert a slight pull upon the disk to cause the tongue 7 to flex inwardly to allow passage of the button through the slot.

While the button-engaging edge of the tongue 7 is shown as defining a straight edge, which is the preferred form of the device, this may, if desired, be modified to provide a slight concavity to insure self-centering of the tongue with respect to the shirt button while the device is being worn.

Also, instead of permanently securing the cord to the necktie by means of stitches, other securing means may be adopted, such as the hooks described in my Patent No. 2,013,061, whereby the necktie holder may be manufactured and sold as a separate article of wear for detachable assembly with a necktie. In the case when the necktie holder is permanently attached to a necktie, the thin flexible disk does not interfere with the washing or dry cleaning of the necktie.

While I have described and illustrated a preferred embodiment of the invention, manifestly various changes in construction and design may be made in my necktie holder without departing from the spirit of my invention as defined in the following claims.

I claim:

1. A holder for four-in-hand neckties comprising a flexible elastic cord defining a loop having its free ends adapted to be secured to the rear face of one end of a necktie and a disk of thin, stiffly-flexible material slidably strung upon the cord, said disk having a slot extending horizontally crosswise of the disk and a tongue extending vertically into the slot and normally lying in the plane of the disk but flexible out of the plane of the disk.

2. A necktie holder as set forth in claim 1 in which the cord is composed of stretchable textile material.

3. A necktie holder as set forth in claim 1 in which the disk is made of a plastic.

4. A necktie holder as set forth in claim 1 in which the cord is permanently secured to a necktie.

5. A necktie holder as set forth in claim 1 in which the cord passes through a pair of relatively widely spaced apart apertures in the disk located above the slot.
